ROLLING MILL SYSTEM

Clarence J. Klein, Steubenville, Ohio

Application December 16, 1936, Serial No. 116,230

17 Claims. (Cl. 80—32)

My invention relates to rolling mill systems and is particularly applicable to apparatus for handling strip metal after it has passed through the finishing stand of a rolling mill. The term "strip metal" or "strip", is herein used to designate metal which is rolled in lengths many times greater than its width and such as is usually referred to in the trade as strip, sheet, and strip sheet material.

After strip material has been passed through the finishing stand of a rolling mill, the modern practice is to coil the strip in suitable coils by means of a power-driven coiler, reel or winding drum. The end of the strip must be secured in some fashion to the reel, which has a cylindrical surface on which the material is coiled. In order to fasten the strip to the reel, the mill has to be at rest so that the workmen will have an opportunity to fit the end of the strip into the gripping notch usually associated with the reels now in use. It is also necessary that the end of the strip be sheared square to fit in the gripping notch or other fastening device associated with the reel. Furthermore, it is not possible to finish the strip to gauge unless the mill is being continuously operated; consequently, it is necessary to discard a considerable length of the strip which first comes through the mill. In general, even with experienced workmen, several minutes are consumed before the strip is securely fastened to the reel and the mill and reel can be started and the mill be driven at commercially desirable speeds.

It is customary after a coil has been formed to the desired size to strip the coil from the reel and to pick up the coil by a crane or by a suitable truck or other handling apparatus and convey the coil to a suitable storage space. The surface of the coiled metal is usually highly finished and it is essential that the coils, which are of great weight, be carefully handled to prevent unnecessary marking and consequent injury of the material both on the inside and the outside of the coil. Such marking reduces the commercial value of the material. Sometimes the handling arrangements are not immediately available at the time desired, and the operation of the mill has to be suspended until coil-handling equipment is available so that the finished coil may be taken from the mill and a new coil can be started on the reel.

By my invention I provide apparatus which will allow the strip to be immediately wrapped around the reel without preliminary shearing of the ends, which are commonly fish-tailed and

uneven, and without stopping the mill so that a very short period of time is required to wrap a sufficient number of turns around the reel to securely hold the strip in winding contact with the reel. Consequently, the mill can be run at a commercial speed within a very short time and thus increase to a measurable extent the output of the mill. Furthermore, the bending of the strip caused by the gripping means on the commonly used reel is such as to cause undesirable marking for a number of turns of the finished strip. By the use of my invention, there is a considerable saving in scrap losses, as such markings are less frequent with apparatus of the type which I have invented, and all the strip in the coil is rolled at gauge for practically its whole length.

In general, my apparatus comprises a reel or winding drum by which the strip may be coiled around the reel as it emerges at a comparatively high rate of speed from the mill and means for stripping the finished coil from the mill and transporting it away from the reel. The coil may then be conveyed to weighing apparatus without undue handling and thence to a storage space outside the longitudinal center line of the mill. To accomplish this I provide means which can be moved into position to wrap the strip around the reel; means which can be moved into position under the coil while on the winding drum to support the weight of the coil while it is being stripped therefrom; means for moving the support with the coil to a clear position beyond the reel, whereupon the coil support is retracted and the top of the support in contact with the coil is tilted so as to cause the coil to roll off the support and onto a conveyor by gravity. The coil then moves along the conveyor to a weighing platform and from the weighing platform to a storage space.

In the accompanying drawings wherein like numerals represent like parts throughout the drawings, I have shown for purposes of illustration only a preferred embodiment of my invention.

Figure 1 is a plan view, partly in section, of an arrangement of apparatus made according to my invention;

Figure 2 is a longitudinal vertical section along the line II—II of Figure 1;

Figure 3 is a schematic elevational view showing the wrapping device in position for wrapping the strip around the winding drum; and

Figure 4 is a similar view showing the wrap-

ping apparatus in retracted position away from the winding drum.

In the drawings, the numerals 2 and 3 represent the housings of a 4-high rolling mill, 5 and 6 represent the working rolls and backing-up rolls, respectively, of the mill, and 7 represents an idling roll interposed between the exit side of the working rolls 5 and the winding drum or reel 8. Conventional means for driving this winding drum are designated generally as 9.

Associated with the winding drum or coiler 8 is a strip-wrapping mechanism or belt-wrapper 10. The winding drum and the strip-wrapping apparatus are arranged along the center line of the mill with which they are associated. This wrapping apparatus is movable into and out of wrapping engagement with the winding drum 8 by means of a piston rod 11, attached to a piston movable in cylinder 12, which cylinder may be operated by fluid such as air or water. The operating connections for the cylinder are not shown. The strip-wrapping apparatus may be of any usual type such as shown in Figures 2, 3 and 4, and it is so arranged that the longitudinal axis of the apparatus is along the longitudinal axis of the rolling mill and the longitudinal axis of the coiler with which the apparatus is associated. The belt wrapper consists of two spaced apart side plates 13 on which are mounted linkages 14, 15, controlled by springs 16. Link 14 is rotatably secured to plate 13 at 17 and to link 15 at 18. Midway of their length, the links 15 are joined by a cross member 19 trunnioned to the links so that the member 19 can rotate about its longitudinal axis. A connecting plate 20 is secured between the side plates 13, and between plate 29 and member 19 the springs 16 are interposed, the action of which springs tends, through the force exerted against member 19, to rotate link 15 clockwise about joint 18. Rotatably secured between the lower ends of links 15 is a roller or pulley 21 which is constrained to move in a straight line by means of member 22, which is slidably received in track 23 secured between plates 13. Rotatably secured between plates 13 and in fixed position are rollers or pulleys 24, 25 and 26. Journaled between plates 13, preferably on the same centers as pulley 26, is a link 27 which carries wrapping rollers 28 and 29 rotatably secured thereto. Link 27 can be rotated around its point of attachment to plate 13. A lap belt 30, which may conveniently be of rubber and fabric construction, passes around rollers 21, 24, 25, 26, 27 and 29, as shown particularly in Figures 3 and 4. It will be observed that under the action of spring 16, exerted through linkage 14, 15, and the weight of link 27 and associated rollers 28 and 29, the tensioning roller 21 will cause the belt 30 to assume the position shown in Figure 4, when there is no other force exerted against belt 30. When the belt is moved against reel 8, tensioning pulley 21 will be moved to the right, as shown in Figure 3, springs 16 will be compressed, and link 27 and associated pulleys 28 and 29 will assume the upright position shown in Figure 3. The belt is then in position for causing the strip to be wrapped around the reel 8.

The supporting plates or frame 13 are mounted on a carriage 31 which is moved back and forth along a convenient track 32 by the movement of piston rod 11. Movement of frame 13 back and forth will cause the belt to move out of and into position for wrapping the strip around the reel 8. The wrapping position is shown in

Figure 3 and the non-wrapping position in Figure 4.

When it is desired to coil a reel of strip material, the belt wrapper is moved into the position shown in Figure 3 by the movement of piston rod 11 to the right and the strip 33 is passed over the idling roll 7 and between belt 30 and reel 8, which reel is turned counterclockwise as shown in Figure 2. The strip is then held between the belt 30 and the outside of the winding drum 8 until several turns have been made on the drum, whereupon the wrapping apparatus is retracted by means of the piston rod 11 to the position shown in Figure 4, where it is wholly out of engagement with reel 8.

Positioned below the winding drum 8 is coil-handling apparatus 34, such as described and claimed in my copending application for Coil-handling apparatus, Serial No. 116,229, filed December 16, 1936, now Patent 2,156,695. As set forth in said application, the cradle 35 can be raised into position to support the formed coil on the reel or winding drum 8, which reel is of the collapsible type. After the coil has been finished, the reel is collapsed and the weight of the coil is supported by cradle 35 and by means of a stripping member (not shown), the coil is stripped from the reel and the cradle 35 is moved to the discharge position beyond the center line of the rolling mill. The movement of the coil-handling apparatus is accomplished by a piston rod 36 movable in cylinder 37. The cradle is raised or lowered by the operation of the piston 50 moving in cylinder 31. When the stripped coil has reached the position shown in chain lines 38 (Figure 1), cradle 35 is lowered whereupon the coil will roll by gravity onto conveyor 39.

Conveyor 39 comprises a number of rollers 40, rotatably supported on guides 41. The top plane of the conveyor slopes slightly downward to the left or away from the coil handling apparatus 34. At the end adjacent the coil handling apparatus the top plane of the conveyor is at a level with the top left upper face of the cradle 35 when the cradle is in the lowermost position as shown in Figure 2. By inspection of Figure 2, it will be seen that the top surface of cradle 35 slopes upwardly to the right when the cradle is in the lowered position as shown in that figure. Consequently a coil supported on that surface will roll off of the cradle 35 and on to the conveyor 39. A portion 42 of the conveyor is arranged over a scale pit 43, and a scale of ordinary construction is attached to this portion of the conveyor so that coils placed on this section of the conveyor may be weighed. A depression 44 is provided on the conveyor guides 41 in which a stop such as an ordinary upright round bar can be inserted to hold the coil in place while it is being weighed. As soon as the coil has been weighed, the stop is removed and the coil will move under gravity to the end of the storage space.

I have shown in chain lines a coil 45 on scale pit 43 and coils 46, 47 and 48 on the storage space at the end of the conveyor 39.

It is to be observed that the belt wrapper and the coil-handling apparatus must be arranged so that they are not in engagement with the coil at the same time and that the longitudinal axis of the belt-wrapper and the longitudinal axis of the coil-handling apparatus are disposed at substantially right angles to one another.

With apparatus constructed according to my invention, it is not necessary that the end of the

strip coming from the finishing roll 5 of the mill be squared and it is not necessary that the speed of the mill be unduly reduced.

The end of the strip 33 is rapidly and expeditiously secured to the winding drum 8 through the aid of the belt-wrapper and the material is not marked during the coiling thereof, or by subsequent handling. As soon as the coil has been completed on the winding drum, it is stripped therefrom by means of the coil-handling apparatus which I have mentioned and conveyed transversely to the longitudinal axis of the mill to a position beyond the center line of the mill and in line with the conveyor 39. By operation of the coil-handling apparatus, the reel may then be transferred from the coil-handling apparatus to the conveyor 39 by the action of gravity and it may then be moved along conveyor 39, first, to the weighing pit 43 and thence to a desired storage position on the conveyor.

The reel or winding drum in a mill of this character necessarily occupies a fixed position directly in line with the pass or longitudinal axis of the rolling mill. The belt-wrapper and the coil-handling apparatus must both operate in juxtaposition to this reel. Consequently, the present system provides an arrangement wherein the wrapping apparatus may be advanced so that the belt engages the reel to start the winding of the strip while the coil stripper or handling apparatus is retracted from the reel. After the coil has been started and a few turns of strip wrapped around the reel, the wrapper is retracted, leaving a free passage for the coil-handling apparatus to come into position to remove the coil from the reel. By using a type of coil-handling apparatus that removes the coil from the reel and carries it to one side thereof and thus beyond the pass line of the mill, the coil is carried clear of the wrapper, reel, and mill to a point where it can be readily disposed of. Moreover, the provision of a run-out conveyor at one side of the roll pass allows the coils to be disposed of without interfering with the operation of the wrapper or of the mill and enables the wrapper to be positioned in line with the mill so that the longitudinal axis of both are in substantially the same line.

It is apparent that by the use of my invention, the time required for starting material on the reel is greatly reduced, the material is not marked and can be expeditiously and properly handled without depending on other equipment. The output of the mill is very considerably increased, due to the smaller amount of time during which the speed of the mill is reduced, and there is a considerable reduction in scrap loss. The total cost of strip and sheet manufacture is, therefore, considerably reduced.

While I have described the preferred embodiment of my invention, it will be understood that the invention is not limited to the apparatus described, but that it may be otherwise constructed and embodied within the scope of the following claims.

I claim:

1. In a rolling mill system, a rolling mill, a reel, a belt wrapper for cooperation with the reel, the transverse vertical axis of the reel and the longitudinal axis of the mill being in substantially the same planes and coil handling apparatus vertically movable from a position below the reel to a position closely adjacent thereto, the belt wrapper being arranged for independent operation into and out of operating position with

the reel while the coil handling apparatus is in a position below the reel.

2. In a rolling mill system, a rolling mill, a reel on which the material to be rolled is coiled, a belt wrapper for cooperation with the reel and movable into and out of engagement therewith, and coil handling apparatus vertically movable from a position below the reel into a position adjacent the reel to contact the material wound thereon, there being sufficient clearance between the coil handling apparatus when in the position below the reel and the belt wrapper so that the belt wrapper can move into and out of engagement with the reel, the longitudinal vertical axis of the reel and the longitudinal vertical axis of the coil handling apparatus lying in substantially the same plane.

3. In a rolling mill system, a rolling mill, a reel on which the rolled material may be coiled, a belt wrapper movable into and out of engagement with the reel for coiling the material thereon at the beginning of the coiling operation, and coil handling apparatus vertically movable from a position directly below the reel and also laterally of the reel, said wrapper being movable into and out of engagement with the reel when the coil handling apparatus is below the reel, both said belt wrapper and coil handling apparatus being arranged for independent operation into and out of operating position with the reel at alternate periods, the path of operation of said coil handling apparatus being transverse to the longitudinal, vertical axis of the mill.

4. In a rolling mill system, a rolling mill, a reel on which the material rolled by the mill may be wound, said reel being in line with the pass line of the mill, a belt wrapper for cooperating with the reel in line with the pass line of the mill, the transverse vertical axis of the reel and the longitudinal vertical axis of the mill being in substantially the same plane, coil handling apparatus movable from a position below the reel to a position to engage the material wound thereon, said apparatus being also movable in a plane parallel to the longitudinal axis of the reel, said belt wrapper being movable into and out of operating position with respect to the reel, while the coil handling apparatus is in a position below the reel, and a runout conveyor, the longitudinal vertical axis of which is substantially parallel to the longitudinal vertical axis of the mill and spaced therefrom.

5. In a rolling mill system, a rolling mill, a reel on which material may be wound as it comes from the mill, a belt wrapper for cooperating with the reel at the beginning of the winding operation, coil handling apparatus movable from a position below the reel to a position to engage the material on the reel, said apparatus being movable in a plane parallel to the longitudinal axis of the reel whereby a coil of material thereon may be carried from the reel to a discharge point, said belt wrapper being movable into cooperating position with the reel, while the coil handling apparatus is below the reel.

6. In a rolling mill system, a rolling mill, a reel on which material may be wound as it comes from the mill, a belt wrapper for cooperating with the reel at the beginning of the winding operation, coil handling apparatus movable from a position below the reel to a position to engage the material on the reel, said apparatus being movable in a plane parallel to the longitudinal axis of the reel whereby a coil of material thereon may be carried from the reel to

- a discharge point, said belt wrapper being movable into cooperating position with the reel, while the coil handling apparatus is below the reel, and a runout conveyor at the said discharge point to receive the coil from coil handling apparatus.
7. In a rolling mill system, a rolling mill, a reel on which material may be wound, a belt wrapper for cooperating with the reel to wind material thereon, coil handling apparatus movable from a position immediately below the reel to a position adjacent thereto for supporting the wound material on the reel, means on the apparatus for stripping the coil from the reel, said apparatus being movable parallel to the longitudinal axis of the reel to a discharge point therebeyond, said coil handling apparatus having all parts thereof completely out of the line of travel of the wrapper when the apparatus is below the reel, and a conveyor at the coil discharge point, said conveyor being substantially at right angles to the longitudinal axis of the reel.
8. In a rolling mill system, a rolling mill for rolling strip material, a reel upon which the strip is coiled, coil handling apparatus having a part thereof movable vertically from a position below the reel to a position adjacent thereto for supporting the coiled strip, said apparatus being movable to carry the coiled strip in a plane along the longitudinal axis of the reel to a position clear of the reel, and a belt wrapper movable into and out of engagement with the reel when the coil handling apparatus is in position below the reel.
9. In a rolling mill system, a rolling mill, a reel, a belt wrapper for cooperation with the reel, the transverse vertical axis of the reel and the longitudinal axis of the mill being in substantially the same planes and coil handling apparatus vertically movable from a position below the reel to a position closely adjacent thereto, the belt wrapper being arranged for independent operation into and out of operating position with the reel while the coil handling apparatus is in a position below the reel, and a runout conveyor the longitudinal vertical axis of which is substantially parallel to the longitudinal vertical axis of the mill and spaced therefrom.
10. Apparatus for use in connection with a rolling mill system comprising a reel on which the rolled material may be wound, a belt wrapper movable into and out of cooperative relationship with the reel for wrapping the material around the reel at the beginning of the reeling operation, and coil handling apparatus movable vertically from a retracted position directly below the reel to a raised position to engage and support the material wound on the reel and movable laterally from a position directly below the reel to a coil discharging position beyond the reel, the path of movement of the coil handling apparatus being in a plane which is parallel to a vertical plane passing through the longitudinal axis of the reel.
11. Apparatus for use in connection with a rolling mill system comprising a reel on which the rolled material may be wound, a belt wrapper movable into and out of cooperative relationship with the reel for wrapping the material around the reel at the beginning of the reeling operation, and coil handling apparatus movable vertically from a retracted position directly below the reel to a raised position to engage and support the material wound on the reel and
- movable laterally when in the retracted position from a position beyond the reel to a position beneath the reel while the belt wrapper is in cooperative relationship with the reel.
12. Apparatus for use in connection with a rolling mill system comprising a reel on which the rolled material may be wound, a belt wrapper movable into and out of cooperative relationship with the reel for wrapping the material around the reel at the beginning of the reeling operation, and coil handling apparatus movable vertically from a retracted position directly below the reel to a raised position to engage and support the material wound on the reel and movable laterally when in the retracted position from a position beyond the reel to a position beneath the reel while a coil is being wound on the reel.
13. Apparatus for use in a rolling mill system, comprising a reel on which the rolled material may be wound, a belt wrapper movable into and out of cooperative relationship with the reel for wrapping the material around the reel at the beginning of the reeling operation and coil handling apparatus movable vertically from a position where it will not retain a coil to a position where it will support and retain a coil and movable laterally from a position directly below the reel to a coil discharging station beyond the reel.
14. Apparatus for use in a rolling mill system, comprising a reel on which the rolled material may be wound, a belt wrapper movable into and out of cooperative relationship with the reel for wrapping the material around the reel at the beginning of the reeling operation, coil handling apparatus movable vertically from a retracted position where it will not retain a coil to a raised position where it will support and retain a coil and movable laterally from a position directly below the reel to a coil discharging station beyond the reel, and a runout conveyor the longitudinal vertical axis of which is substantially parallel to the longitudinal vertical axis of the mill, the surface of the runout conveyor being positioned to receive the coil from the coil handling apparatus when it is in the retracted position at the coil discharging station.
15. Apparatus for use in connection with a rolling mill system comprising a reel on which the rolled material may be wound, a belt wrapper movable into and out of cooperative relationship with the reel for wrapping the material around the reel at the beginning of the reeling operation, and coil handling apparatus movable vertically from a retracted position directly below the reel to a raised position to engage and support the material wound on the reel and movable laterally from a position directly below the reel to a coil discharging position beyond the reel, the path of movement of the coil handling apparatus being in a plane which is parallel to a vertical plane passing through the longitudinal axis of the reel, said coil handling apparatus being movable laterally when in the retracted position beneath the reel while a coil is on the reel.
16. In a rolling mill system, a rolling mill, a reel on which material may be wound as it comes from the mill, a belt wrapper for cooperating with the reel at the beginning of the winding operation, coil handling apparatus movable from a position below the reel to a position to engage the material on the reel, said apparatus being movable in a plane parallel to the longitudinal axis of the reel whereby a coil of material thereon may be carried from the reel to a discharge

- point, said coil handling apparatus being movable laterally when in the retracted position beneath the reel while a coil is being wound on the reel.
- 5 17. In a rolling mill system, a rolling mill, a reel on which material may be wound, a belt wrapper for cooperating with the reel to wind material thereon, coil handling apparatus movable from a position immediately below the reel 10 to a position adjacent thereto for supporting the wound material on the reel, means on the apparatus for stripping the coil from the reel, said apparatus being movable parallel to the longitudinal axis of the reel to a discharge point therebeyond, said coil handling apparatus being 5 movable when in the retracted position laterally from the discharge point to a position beneath the reel while a coil is on the reel.

CLARENCE J. KLEIN. 10
